UNITED STATES PATENT OFFICE.

GEORGE P. SCHMITT, OF OAKLAND, CALIFORNIA.

HOT-AIR HEATER.

Application filed March 17, 1924. Serial No. 699,753.

This invention relates to hot air heaters and in particular to heaters adapted to the use of gaseous fuel.

The outstanding feature of this invention is the provision of a heater constructed in such a manner that the products of combustion from the burner are delivered to the flue without coming in contact with the fresh air circulated within the heater enclosure, thereby eliminating any obnoxious odors or poisonous fumes which necessarily emanate from this form of combustion.

Another feature of this invention is the novel arrangement of the outlet flue with relation to the burner, which flue extends downwardly from the top of the heater unit to a point virtually at the burner level which provides a maximum radiation surface and delivers the products of combustion to the outside at a minimum temperature.

I have shown my heater as applied to the floor of a room with the heater casing and burner below the level thereof and a register covering the opening above the heater and having the main burner control valve and pilot control constructed to extend to the top level of the register, but it is to be understood that the heater may be placed upon a suitable support in the basement and used as a furnace with minor changes in the details of arrangement without departing from the main features of the heater construction.

The object of this invention is to construct a heater which is compact, inexpensive in operation and easily controlled.

Another object is to construct a heater which will deliver a maximum degree of fresh hot air with a minimum consumption of fuel.

Other objects and advantages of my invention will appear with reference to the subjoined specification and accompanying three sheets of drawings, in which:

Figure 1 is a plan of my heater in place below the floor of a room and showing the register and arrangement of control valves, main burner, pilot arrangement and sight opening to the main burner.

Fig. 2 is a cross section taken at line 2—2 of Fig. 3 and showing the relative arrangement of the outer and inner casings and location of the heater with relation to both casings.

Fig. 3 is a vertical mid-section taken at

the lines 3—3 of Figs. 1 and 2 and showing the entire arrangement of the heater, fuel connections and air circulation.

Fig. 4 is a vertical section of the heater unit taken at right angles to Figs. 2 and 3 and at the line 4—4 of Fig. 2, the outer and inner casings being omitted.

Fig. 5 is a plan of the burner.

Referring to Figs. 1, 2 and 3 of the drawings it will be seen that I have shown my heater as applied to the floor of a room and I will therefore describe it accordingly. The outer casing (10) is of rectangular shape and preferably constructed of heavy galvanized material and fits within an opening (11) in the floor and to the edge of which it is attached in any suitable manner. The lower edges of this casing are flanged inwardly and support a base plate (12) having a central opening (13) in which the combustion chamber casting (14) or housing is centrally located.

A grilled register (15) fits within the upper end of the outer casing (10) and rests upon the floor, and an inner casing (16) of rectangular shape is attached to the lugs (17) formed at the under side of the register. This casing flares outwardly from its top edge and ends a distance above the housing (14). An air circulation passage (18) is thus formed between the outer casing (10) and inner casing (16) and extends downwardly from the outer rows (19) of the openings in the register (15) to the base plate, and the space within the inner casing (16) communicates with the central openings (20) of said register.

The heater element comprises duplicate castings or housings (14) and (21) which are of comparatively thin metal and substantially T-shaped in cross section. These castings are of hollow construction and provided with elongated extensions (22) of rectangular shape and communicating chambers (23). Said extensions (22) and chambers (23) open outwardly at opposite sides of the housings, and the extension (22) of the housing (14) fits within the opening (13) in the base plate and rests upon lugs (24) formed upon said housing.

Flanged cover plates (25) and (26) fit within the upper edges of the housings (14) and (21) and are provided with a plurality of equally spaced flanged openings (27) and

(28) to which are fitted a plurality of radiating columns (29). These columns are preferably constructed of galvanized sheet-metal pipe and provide means for spacing the housings (14) and (21) and serve to radiate the heat passing therethrough from the burner.

In the drawings I have shown four of these radiating columns, but in larger furnaces it will be necessary to provide many columns, the number depending upon the inside area of the furnace and radiating surface required.

An outlet housing (30) fits over and embraces the upper housing (21) and consists of a rectangular shell having a flanged extension (31) fitting around the upper edge of the extension (22) of said housing, and rests upon a baffle plate (32) extending from one end thereof to near the other. A neck or thimble (33) is integrally formed with the outlet housing (30) and extends downwardly at one end thereof and at right angles to the chamber (34) of the housing 25 and communicates therewith through an opening (35). An opening (36) is formed at one end of the baffle plate (32) and communicates with the chamber in the housing (21) and the chamber (34) of the outlet 30 housing (30).

A pipe (37) extends downwardly from the neck (33) and through an opening in the plate (12) and is connected to a flue (not shown). A burner (38) is positioned 35 within the opening of the extension (22) of the housing (14) and is held therein by a strap (39) secured at opposite ends to the base plate (12). This burner is of an ordinary type and is provided with a gas 40 inlet pipe (40) and burner tip as shown in Fig. 3. A feed pipe (41) from the gas supply extends into the outer casing (10) below the floor and is provided with branch pipes having control valves (42) and (43) 45 for the main burner inlet (40) and pilot valve (44). The upper ends of the valve stems (45) of the control valves (42) and (43) are squared and extend into openings in the register and a key is used to manipulate 50 said valves to control the flow of gas from the pipe (41).

The pilot burner (44) is located at the rear end of the burner (38) and is provided with a slotted opening which projects a fan-shaped flame into the combustion chamber above the main burner as shown in Fig. 3. A pipe (46) leads from the register (15) and extends through the base plate (12) and is held thereby. This pipe extends to a position 55 above the top of the pilot burner (44) and said pilot may be ignited by turning the valve (43) and holding a match over the upper end of this pipe. This method of igniting the pilot each time to light the main burner saves considerable gas and obviates

any danger of the pilot being accidentally extinguished.

A U-shaped rod (47) embraces the entire heater unit and the ends thereof extend through openings in the base plate (12) and 70 through the ends of the burner strap (39) and are securely held in place and drawn against the plate (12) by nuts (48).

The contacting edges of the cover plates (25) and (26) and housings (14) and (21) 75 may be sealed by means of any well known cement suitable for this purpose.

A sight opening (49) is provided in the upper housing (21) to enable the operator to properly adjust the burner from the room 80 above by manipulation of the burner valve (42).

In operation, hot air from the burner travels upwardly from the chamber in the housing (14) to the radiating columns (29) 65 and is equally distributed therethrough to the upper housing (21) and against the baffle plate (32), which plate deflects it to the opening (36), thence through the chamber (34) of the outlet housing (30) to the neck 90 (33) and pipe (37) to the flue. It will thus be seen that all poisonous products of combustion are drawn from the burner and delivered directly to the flue, and that the heat radiating surfaces of the housings and 95 columns tend to draw and continuously circulate fresh air from the room through the passage (18) and upwardly within the inner casing (16) to the register openings (20).

Having thus illustrated and described my invention in its preferred form, I wish it understood that the same may be modified as practice suggests. Therefore, the patent protection that I desire to secure is all of that which comes within the scope and spirit 100 of my invention as set forth in the following claim.

Claim:

In a heater adapted to have a flue connected therewith, the combination of an 111 outer casing and an inner casing, said inner casing being open at the bottom, a register covering both casings, a cold air passage between the outer casing and inner casing, a heater unit within the inner casing, a 116 burner therefor, a hot air passage between said heater unit and inner casing leading to the register and an outlet passage leading through the inner casing and the outer casing from the top of the heater unit to a 120 position virtually at the burner level below the outer casing and thence to the flue and a baffle plate disposed in proximity to the top surface of said heater unit having an opening disposed furthest from said outlet 125 passage whereby the heated gases are caused to travel parallel to said register and adjacent thereto.

In testimony whereof I affix my signature.
GEORGE P. SCHMITT.
